UNITED STATES PATENT OFFICE.

LOUIS A. CASGRAIN, OF BEVERLY, MASSACHUSETTS, ASSIGNOR TO UNITED SHOE MACHINERY CORPORATION, OF PATERSON, NEW JERSEY, A CORPORATION OF NEW JERSEY.

SOLE-LAYING MACHINE.

Application filed June 11, 1920. Serial No. 388,163.

To all whom it may concern:

Be it known that I, LOUIS A. CASGRAIN, a citizen of the United States, residing at Beverly, in the county of Essex and State of Massachusetts, have invented certain Improvements in Sole-Laying Machines, of which the following description, in connection with the accompanying drawings, is a specification, like reference characters on the drawings indicating like parts in the several figures.

This invention relates to the manufacture of footwear and is herein illustrated as embodied in a machine for laying rubber soles on shoes.

The illustrative machine is of that type in which fluid means are provided for operating both the jack or support for the lasted shoe and the sole laying pad or presser. Hitherto it has been customary to force fluid into pressure chambers connected with the jack and presser to operate these members and then, when the sole laying operation was complete, to permit the fluid to escape so as to relieve the pressure. One manner of accomplishing this has been to let in water from a pressure main and then to permit it to escape to a drain. This procedure, besides being wasteful of the water used, is unsatisfactory because the degree of pressure in water mains varies with different mains and with the height in any particular factory of the floor upon which the sole laying machine is located. In order to obviate these disadvantages the present machine is provided with a self contained liquid system which uses the liquid over and over again. Such a system not only saves liquid which would formerly have been wasted and ensures a more uniform pressure, but by providing positively operated means for moving the liquid to and from the points at which pressure is desired, makes the operation of the machine more rapid since the delay which formerly occurred during the drawing off of the liquid is obviated.

Other novel features comprise improved means for locating the sole with respect to the lasted shoe, an improved valve mechanism for controlling the flow of liquid, and an improved construction of the jack whereby the lasted shoe may be held firmly without liability of being disfigured.

These and other features of the invention, including certain details of construction and combinations of parts, will be described as embodied in an illustrative machine and pointed out in the appended claims.

Referring now to the accompanying drawings,

Fig. 1 is a perspective view of a complete machine embodying the present improvements;

Fig. 2 is a sectional front elevation;

Fig. 3 is a detail sectional view of one of the jack post adjustable connections;

Fig. 4 is a detail broken out perspective view of a casting member which includes the valve chambers;

Fig. 5 is a detail sectional view of the device for locking the sole-locating plate in operative position;

Fig. 6 is a sectional elevation illustrating the valves and connections for controlling the hydraulic mechanism;

Fig. 7 is a section on line 7—7 of Fig. 6;

Figs. 8, 9, 10 and 11 are transverse sectional views through the pressure box, illustrating successive steps in the operation of the machine;

Fig. 12 is a detail plan view of one end of the sole locating plate, illustrating also one form of heel gage;

Fig. 13 is a perspective view of another form of heel gage;

Fig. 14 is a perspective view illustrating the means for locking the heel gage in adjusted position;

Fig. 15 is a section on line 15—15 of Fig. 7 looking in the direction of the arrows.

Before entering upon a detailed description of the construction of the machine, its general mode of operation will be briefly described. Referring first to Figs. 8 to 11, inclusive, a sole 100 is placed upon a flexible

pad in the form of a rubber diaphragm 17 which is supported by water 19 and an upwardly spring-pressed plate 21 as indicated in Fig. 8. A lasted shoe 200 is next placed

upon the sole as indicated in Fig. 8. A treadle is then depressed to cause water under pressure to flow first to a jack, the toe post 23 of which is indicated in Fig. 10, the water serving to depress the jack and with

it the shoe as indicated in Fig. 10. The passage through which water flows to the jack

is then closed while the water is under considerable pressure, thus locking the jack and shoe in the position shown. Water is next caused to flow to the pad or pressure box 25 to distend the pad or diaphragm 17 and cause it to assume a position such as that shown in Fig. 11 to press the body of the sole against the bottom of the shoe and to roll the edge of the sole up against the lower margin of the shoe. When the pressure in the pad box has reached a predetermined desired degree, it is released, and subsequently the pressure on the jack is also released; and the shoe, with its sole properly laid, is removed from the machine. In the illustrative machine, depression of a treadle to throw in a suitable clutch causes first application of pressure to the jack, then application of pressure to the pad or diaphragm, and finally release of the pressure on the diaphragm, the release of the pressure on the jack being accomplished manually.

A suitable frame for the machine is illustrated at 27 in Fig. 1, said frame having a shelf or ledge portion 29 to support the liquid container or pad box 25. To provide for securing the box 25 in proper operative position and yet permit it to be removed, devices such as illustrated in Figs. 1 and 2 may be employed, each of said devices comprising a lug 31 of the box which is connected to a lug 33 of the frame by a screw.

Secured to the top of the box 25 is the sole receiving pad 17 of resilient elastic material such as rubber, which may be reinforced if desired, the marginal edges of said pad being clamped between the flange of the box and a rim 34 corresponding in outline with the outline of the flange, the clamping being effected by any suitable means such as bolts, as indicated in Fig. 1.

Portions of the clamping rim 34 are formed (Figs 1 and 8 to 11 inclusive) to present parallel guide lugs 35 for the edges of a curved sole-locating plate 37, said plate having two sole-shaped openings 39, one for a right sole and the other for a left sole. Adjustably mounted on the plate 37 and preferably slightly overlapping each opening 39 are last guiding or shoe guiding lugs 41, one of said lugs being at the toe portion of each opening and two along one side of said opening. The plate 37 is formed with two edge recesses 43, one of which is shown in Fig. 1 (see also Fig. 5), said recesses being properly located so that either one of them will co-act with a spring actuated locking bolt to hold the plate 37 firmly in proper longitudinal position with one or the other of the two openings 39 in accurate location above the flexible pad 17. The bolt 45 (Fig. 5) for locking the sole locating plate 37 in proper longitudinal position is mounted in a lug 47 formed on one of the flanges 34 and is pressed toward locking position by a

spring 49, a lever 51 being provided for withdrawing the bolt and holding it withdrawn when desired. Since the plate 37 is slidable in the direction of its length and easily removable, one of such plates can be changed for another according to the size of shoe and sole to be operated upon. It is curved in order to conform approximately to the longitudinal curve of a shoe bottom. By having a number of the plates 37 with different sizes or shapes of sole openings 39 cut for rights and lefts, there will be no possibility of mismatching the work. It is desirable to explain here that it is customary in the manufacture of rubber sole footwear to finish a lot containing an equal number of rights and lefts. The plate 37 that is being used for a certain lot can either be shifted along alternately from position for rights and lefts, or it can be left in one position until all the rights are finished and then shifted to position for finishing all of the lefts in that particular lot.

Since the sole laying pressure is obtained by varying the volume of a mobile inelastic substance such as water in the box 25 so that the pad 17 varies as to its height relatively to the plate 37, it is desirable to render it certain that there shall be no liability of so placing a sole through an opening 39 that an edge portion of such sole could, when laying pressure is applied, get pinched between the pad and the plate. In other words, it is desirable to render it certain that no portion of a sole when being placed in an opening 39 can be slipped under any portion of the plate 37. To effect this, I provide means for normally holding the pad 17 close against the under surface of plate 37, as best illustrated in Figs. 2, 8 and 9. For this purpose I provide a pad-supporting plate 21 which has approximately the same longitudinal curvature as the plate 37, said plate 21 being mounted on springs 55 inside of the box 25, and preferably having apertures so that vertical movements of the plate shall not be interfered with by reason of the water or equivalent substance in the box. The heel portion of the plate has an opening to permit it to pass to a position below the plane of the top of a block 57 secured in the box in such location as to limit downward movement of the heel of the sole and last. The springs 55 normally tend to press the plate 21 upwardly far enough to render it certain that the pad or diaphragm 17 will be brought close up against the under surface of the marginal portion of the sole locating plate 37 around the opening 39 as soon as the sole laying operation has been completed and the last and shoe removed from the machine.

In order to cause the lasted shoe to be pushed down into and held in the position shown in Fig. 2 preparatory to letting more

water into the pad box 25, the following construction is provided. The upper portion of the frame 27 is divided and formed with two downwardly extending arms 59 (Figs. 1 and 2), each formed with a slot 70, the lower portion of which is vertical, while the upper portion extends rearwardly at an angle to the lower portion. Extending across the divided upper portion of the frame is a pin 63, secured firmly in place by binding screws 65. Mounted to turn on the pin 63 is the hub of a casting the lower portion of which is formed as a hollow arm 67, the upper portion of the casting being formed as a pipe 69, said pipe communicating with the space in the hollow arm 67 (Fig. 2). Fitted to slide vertically on the hollow arm 67 is a cylindrical member 71, a suitable packing ring being provided to prevent escape of liquid, these two members 67 and 71 forming together an extensible arm. In order to cause this extensible arm 67, 71 to swing on the pin 63 as it elongates, the member 71 is provided with rolls 73 which travel the slots 70 of the frame arms 59. When liquid is forced into and withdrawn from the extensible arm 67, 71 by the means hereinafter described, this arm 67, 71 is first elongated and then shortened. The first movement of elongation causes the rolls 73 to ride down the inclined portions of the slots 70 of the frame arms 59, so as to swing the extensible arm from the normal or idle position in Fig. 1 out to a vertical position so that the whole jack mechanism including the jack posts, presently to be described, will be brought over the last, and further movement will then lower said posts and depress the last to the position shown in Fig. 2. When hydraulic pressure within the extensible swinging arm 67, 71 is released, the arm is shortened and returns to the Fig. 1 position under the influence of a spring 75 (Fig. 2). A plug 77 may be employed to provide for drainage when desired.

As so far described, the construction and operation of the machine are substantially the same as in the machine of my prior application Ser. No. 287,516.

The lower end of the member 71 is formed or provided with a horizontal, laterally extended web 79 adjustably carrying a toe post and a heel post which serve to support the work against the sole laying pressure of pad 21. Each of the post stems 81, 83 is preferably so connected to the member 71 as to be adjustable to a variable distance from the center of thrust of the member 71. In the embodiment of the invention illustrated herein, this adjustability is provided for by forming the lower face of the web 79 with side ribs so formed as to present a guideway 85. Slidably mounted in the guideway are two hollow brackets 87 split at their upper ends (Figs. 2 and 3) and formed to fit snugly

the guideway. Each bracket 87 is provided with an internal lug 89 against which a set screw 91 is adapted to be forced with such pressure as to expand the upper end of the bracket to bind it in the guideway. 70

The externally threaded stems 81, 83 of the toe and heel posts fit internally threaded portions in the lower ends of the brackets 87. Each threaded portion is vertically grooved as at 93, and a spring-pressed ball 75 95 (Fig. 3) is adapted to be held in engagement with one or another of the grooves 93. Raising or lowering of either the heel or toe post is effected by rotating it, the locking ball 95 yielding to permit such rotation and 80 then automatically seating itself in one of the grooves 93.

The rear jack post 83 has swivelled on its lower end a metal contact member 97. In order to provide for engaging the toe portion of the last shoe without injury to the vamp, as well as to ensure that the toe portion shall be properly engaged, an improved water-filled toe pad 99 is provided. This toe pad, which may be made of rubber and have 90 cellular walls, is hollow so as to contain a fluid such as water. An opening in its upper end receives a nipple 101 having a passageway 103 therethrough. The stem of this nipple is externally threaded to receive an internally threaded nut 105, a washer 107 of the shape shown being located between the lower end of the nut and the toe pad 99 so that by screwing the nut down on the nipple the toe pad may be held firmly. The nut is 100 elongated into a sort of sleeve which is threaded internally to receive the lower threaded end of the stem 81, and is threaded externally to receive a cap nut 109, packing 110 being inserted inside the cap nut to ensure a tight joint. The stem 81 is provided with a hexagonal portion 111 to receive a wrench by which the stem 81 may readily be turned to raise and lower it or by which the stem may be held stationary while the cap 110 nut 109 is being tightened or loosened. It will be understood that by unscrewing the cap nut 109, the nut 105 together with the parts held at its lower end may be removed for filling with water or for any other purpose. 115

As has been described, the sole locating plate 37, when adjusted lengthwise, slides over the upper face of the pad 17. To prevent wear of the marginal portion of the pad resulting from sliding movements of the plate 37, I interpose a thin plate 113 between the pad and the sole locating plate as shown in Figs. 8 to 11 inclusive. As shown in Fig. 2, the box 25 is formed near each end with a small hole normally closed by screw plugs 115. These are to enable the box to be filled completely with liquid so as to avoid the presence of air in the box. If at any time the operation of the pad appears to be 120 125 130

ineffective because of the presence of air below the pad, one or both of the screws 115 will be loosened until water begins to flow out, and then closed. In practice any suitable check valve structure may be employed to prevent inflow of air when a screw plug is loosened. A thin plate 117 of spring metal mounted on the plate 21 above the large opening therein is loosely connected 10 with said plate as by pins one of which is shown at 119 passing loosely through holes in plate 21, the object of the loosely connected plate 117 being to cover the large opening in pad supporting plate 21 and properly to 15 support that portion of the pad 17 which is above said opening and the block 57, when the pad or diaphragm 17 is held up in normal position by the plate 21.

To enable a sole locating plate 37 to be 20 employed for a considerable range of sizes and shapes of soles, I employ an adjustable gage one form of which is illustrated in Figs. 1 and 12 and another form in Fig. 13. Referring first to Figs. 1 and 12 the gage 25 comprises a bifurcated member 132 the shank 133 of which, having notches 134, is slidably mounted in a block or housing 135 secured to the plate 37. A spring locking device 136 having a tooth 137 adapted to engage 30 any one of the notches 134 is suitably secured to the block 135 as by a screw 138. One end of the spring projects to form a tip which may be lifted by the finger of the operator to disengage the tooth 137 from a 35 notch 135 to permit the gage to be adjusted in the direction of the length of its shank and relocked in adjusted position. As illustrated in Fig. 13, the bifurcated end of a different form of gage 142 may be curved 40 instead of somewhat angular as in the other figures, and provided with a wiper strip 140 of rubber or equivalent. The reason for providing the gage 142 with a resilient strip such as indicated at 140 in Fig. 13 is to 45 facilitate the locating of certain kinds of soles such as those which are thickened by the addition thereto of an extra layer to provide a heel tap and to aid in laying them. In a sole of the kind referred to the heel tap is of considerably less area than is the heel end of the 50 sole so that the margin of the heel end of the sole overhangs the heel tap to a considerable extent. When such a sole is placed on the pad or diaphragm 17, the heel end of the 55 sole is held raised above the surface of the diaphragm by the heel pad, and, being thin, does not offer a sufficiently stiff edge for sole locating purposes. The gage shown in Fig. 13 is particularly useful in locating a 60 sole of this sort and in aiding in the laying of it. The curved edge of the wiper 140 is adapted to engage the firm rear edge of the heel tap and to underlie the thin margin of the sole so that when the shoe and sole are moved down from the position shown in

Fig. 8 to that shown in Fig. 9, the thin margin of the sole is wiped up evenly.

It will be seen by referring to Figs. 1 and 12 that the last guiding lugs 41 are arranged to engage the lasted shoe at the toe end and at two points along one side and that consequently the longitudinal position of the lasted shoe, whatever its size, is determined by the forward lug 41, and its lateral position by the two lateral lugs 41. In other 70 words, if the bottom of the lasted shoe is smaller than the opening 39, the toe end and one side of the shoe will always be located near one end and near one side of the opening. The purpose of making the gage, 80 whether it be the gage 132 or the gage 142, adjustable in the oblique direction best shown in Fig. 12 is to crowd the toe end of the sole against the forward edge of the hole 39 and one side of the sole against that edge 85 of the hole over which the side lugs 41 project. With this construction a sole somewhat smaller than the hole 39 may be properly placed to receive its lasted shoe and thereby the number of sole locating plates 90 37 necessary to be provided with each machine materially reduced.

As has been explained, water under pressure is supplied first to the jack to engage and depress the lasted shoe, and then to the 95 pad or pressure box 25 to force the diaphragm 17 up about the lower portion of the shoe. Water is supplied to the pad box through the pipe 121 and to the jack through the pipe 123, the latter pipe having a flaring upper end, as shown in Fig. 2, which is connected with the pipe 69 by a properly shaped nut 125 and spring 127, this connection being provided to permit the turning of the pipe 69, together with the members of 100 the jack about the pin 63 as has been described above.

The machine is provided with a self contained water system herein shown as including a reservoir 145 which is fastened by 110 bolts to the top of a cylinder 147 the bottom 149 forming the top of the cylinder. Located in the cylinder is a piston 151 which may be caused at any time to make a complete reciprocation and then come to rest 115 in the position shown in Fig. 6, this reciprocation serving first to force water to the jack and pad box and then to facilitate its withdrawal. The flow of the water is controlled by three valves located in a chambered casting which is integral with the reservoir 145. In order to promote clearness, these valves will be referred to as the jack valve, the reservoir valve and the pad box valve. Referring more particularly to 120 Fig. 6, the jack valve 153 is located at the bottom of a chamber 155 which communicates at its upper end with the pipe 123 leading to the jack; and beneath the valve 125 is a port 157 which communicates with the 130

cylinder 147. This valve is normally held down in closed position by a spring 159; but, when the piston is moved upwardly, the valve is unseated and permits water to be forced up into the pipe 123 to actuate the jack in the manner which has been described above. The pad box valve 161 has a seat in the bottom of a chamber 163 which is directly connected with the pipe 121 leading to the pad box and is acted upon at all times by a spring 165, this spring being considerably stronger than the spring 159 which acts upon the jack valve. Below the pad box valve 161 is a port 167 which, like the port 157 of the jack valve, communicates with the cylinder 147. At about the time the piston starts its upward movement, the pad box valve 161 is closed and does not open until the pressure in the pipe 123 leading to the jack rises to a degree sufficient to overcome the force of the spring 165. The pad box valve 161 thus acts as a sort of relief valve for the jack, the strength of the spring 165 determining the degree of pressure which will be exerted upon the lasted shoe. The moment water ceases to flow through the pipe 123, the jack valve 153 is closed by its spring 159. Turning now to the reservoir valve 169, this valve has a seat at the bottom of a chamber 171 which communicates by a port 173 with the reservoir 145, said reservoir being open to atmospheric pressure and having a loosely pivoted cover 175. A spring 177 of greater strength than that of the spring 161 of the pad box valve acts at all times to tend to close the reservoir valve 169. During the first part of the upward movement of the piston, this reservoir valve 169 is held open, but at or immediately after the closing of the jack valve 153, this valve 169 is permitted to close, and the pad box valve 161 is opened mechanically and held open. Water then flows through the pipe 121 to the pad box, and forces the pad or diaphragm 17 up around the lower portion of the shoe as shown in Fig. 11. Pressure now rises in the pipe 121 and chamber 163 which is in effect an extension of the pipe 121 until it is sufficient to overcome the force of the spring 177 of the reservoir valve, when that valve will be lifted to relieve the pressure and permit water to flow to the reservoir. The tension of the spring 177 thus determines the degree of pressure which will be applied to the sole of the shoe, and it will be noted that this tension may be varied by turning the stem 170 of the threaded disk 172 against which the upper end of the spring bears. At about this time the piston begins its downward movement, the pad box valve 161 being held open by mechanical means, and the reservoir valve 169 also opened and held open if it has closed, the parts coming to rest in the positions shown in Fig. 6. Enough water is maintained at all times in the system so that the pad box 25, the pipe 121 and that part of the cylinder above the piston are always filled with water, the level of the water always being 70 above the bottom of the reservoir. Consequently the amount of water displaced by the rise of the piston is relatively small being estimated at not more than one-sixth of the whole volume of the water, and in 75 some cases not more than one-twelfth.

When the parts come to rest in the positions shown in Fig. 6, the jack valve 153 is closed and the jack is still locked under pressure in its lowered position. In the 80 illustrative machine this valve is not opened and held open by mechanical means as are the other two although it may be so opened if desired, one form of such a means being shown in my prior application Serial No. 85 287,516, but is opened by depressing the horizontal arm of a bell crank lever 179, the upright arm of which is connected by a rod 181 to the upright arm of a second bell crank lever 185 the hub 180 of which is loosely 90 mounted on a stud shaft carried by the wall of the cylinder 147. The outer end of the horizontal arm of this bell-crank lever is located beneath the stem of the jack valve 153 so that this valve is thereby lifted. A 95 coiled spring 187 tends at all times to act upon the hub 180 to hold the upright arm of the bell crank lever against a stop pin 188.

Turning now to the mechanism for reciprocating the piston and for mechanically opening the reservoir valve 169 and the pad box valve 161 and having reference more particularly to Figs. 1 and 6, there is formed in the rear portion of the frame a casing in which is rotatably mounted a shaft 189 having a 100 crank pin 191 to which a wrist pin in the piston 151 is connected by a connecting-rod 193, the crank arms which carry the crank pin 191 being formed as cams 195, 197. Mounted above the shaft 189 is a rod on 105 which are loosely fulcrumed the hubs of two arms. The arm 199 carries a roller 201 which rests upon the surface of the cam 195, the arm when raised being adapted to lift a rod 203 which is connected to the stem of 110 the reservoir valve 169. The arm 205 carries a roller 207 which rests upon the surface of the cam 197, the arm when raised being adapted to lift a rod 209 which is connected to the stem of the pad box valve 161. The 115 cams 195 and 197 are so shaped that when the shaft 189 has made one revolution and come to rest, as it does in the position shown in Fig. 6, the valves 161 and 169 are held open, and when the shaft is rotated the 120 valves are lifted or permitted to close in the following manner. As soon as the piston 151 starts upward, the valve 161 is permitted to close and remains closed while water is being forced past the jack valve 153. As soon 125 130

as the jack valve 153 closes, at which time the pad box valve 161 may be raised slightly by the water pressure, said pad box valve is lifted and the reservoir valve 169 is permitted to close. During the further rise of the piston the valves 161, 169 remain in these positions until near the end of the upstroke of the piston when, if the pressure in the pipe 121 and pad box 25 rises to a sufficient degree the reservoir valve 169 may be lifted slightly by the water pressure. At the same time or prior to that time the jack valve 153 may also be lifted by the water pressure, but whether it is or not is immaterial since the pipe 123 is full of water under pressure. At this time the laying of the sole is completed, the piston is at or almost at the top of its stroke, and the reservoir valve 169 is then opened and held open until the piston has been withdrawn to its lowermost position.

In order to impart to the shaft 189 a single revolution when desired, there is loosely mounted on the shaft a worm wheel 211 driven continuously by a worm 213 which may be connected with any suitable source of power such as an electric motor, not shown. The worm wheel 211 may be connected with the shaft 189 at any time by depressing a treadle, not shown, which is connected to a treadle rod 215, depression of the treadle serving to throw into operation a one-revolution clutch indicated at 217. The clutch mechanism will not be described further since the details of its construction form no part of the present invention and any suitable one revolution clutch may be employed. Below the worm wheel 211 is a pan containing oil into which the wheel dips.

When the machine is to be used, the operator, after seeing that the proper plate 37 is in place and that such plate is in such longitudinal position that the proper right or left opening 39 will be above the pad 17, takes the proper sole to fit that opening and drops it upon the pad with the toe end of the sole against the toe end of the opening and with one side of the sole bearing against that side of the opening which is adjacent to the side lugs 41, the heel gage having been set in position to engage the heel end of the sole.

With the sole thus located, the operator takes the proper last 200 with the upper thereon, and places it upon the sole, using the guide lugs 41 as means for accurately positioning the last and its upper relatively to the sole. In practice it is preferably so to adjust the heel gage that the distance between it and the toe end of the opening 39 is slightly less than the length of the sole so that said sole will buckle up somewhat in its shank portion. When the sole is so placed and hydraulic pressure is exerted below the pad 21, the shank portion of the sole may be

forced up to fit the shoe shank portion without causing such stretching of the shank portion of the sole as might later tend to separate it from the shoe bottom.

After locating the sole and shoe as indicated in Fig. 9, the operator actuates the treadle (not shown) so as to connect the constantly running worm wheel 211 to the shaft 189 and impart to it one revolution. During the first half of the single rotation of the shaft the cam 197 first permits the pad box valve 161 to be closed by its spring, the reservoir valve 169 being still held open by cam 195. The moment that the shaft begins to rotate, it begins to effect a rise of the piston 151 so as to force water to any point toward which it is free to flow. Pad box valve 161 being first closed and held closed by its relatively heavy spring 165 no water can pass through port 167, but the action of the piston forces water through port 157 and lifts the jack valve 153 the water passing into pipe 123 so as to fill the pipe and to produce and increase pressure therein and in the extensible arm 67, 71 so that said arm lengthens in opposition to the pull of spring 75. Owing to the shape of the slots 70, the pressure first carries the jack mechanism from the normal rearwardly swung position, shown in Fig. 1, out to position above the shoe and then down. The latter part of this movement presses the lasted shoe to substantially the position shown in Figs. 2 and 10 at which point the block 57 prevents further downward movement of the shoe, the arresting of further downward movement of the jack preventing further lengthening of the extensible arm. The movement of the piston continues; but, as the arrest of the extensible arm results in stopping the flow of the water past the jack valve 153, the action of its spring 159 seats the valve which insures retention of the jack in the position shown in Figs. 2 and 10. That is, the jack is locked under pressure in that position. In the illustrative machine the jack remains locked in last-holding position until manual operation of the lifter arm 185 effects the opening of the valve so that the ensuing reduction of pressure in the pipe and the extensible arm will permit the spring 75 to return the jack mechanism including the jack posts to normal position as shown in Fig. 1.

Continuation of the first half of the rotation of the shaft and with it the cams 195, 197, then opens the pad box valve 161 and permits the reservoir valve 169 to be closed by its heavy spring 177. Water now is forced through the port 167 and pipe 121 to the pad box 25, the pressure rising until it is sufficient to overcome the resistance of the heavy spring 177 so that the pressure always rises to a predetermined

degree. As pressure in the pad box 25 rises to shift the pad 21 from the position shown in Figs. 2 and 10 to that shown in Fig. 11, the resultant flexing of the pad 5 carries the marginal portions of the sole up around the margin of the lasted upper with a firm uniform pressure, which pressure is localized and made effective against the bottom and lower portions of the sides 10 of the lasted shoe, since the marginal portions of the pad can not be moved because of being held down by the sole locating plate 37. The amount or degree of this laying pressure may be controlled by actuating the stem 170 of the member 172 which bears upon the spring 169. When flexure of the pad reaches such point that further movement is resisted by the lasted shoe, the pad is practically converted into 15 a close fitting mold every portion of which thereafter exerts the same degree of laying pressure as other portions.

The sole laying pressure occurs, as has been described, during the upward movement of the piston. At about the time it begins its downward stroke, the reservoir valve 169 and the pad box valve 161 are opened by the cams and thereafter are held open during the whole downward 20 stroke. The piston thus sucks water back through the pipe 121; and since the valves 169 and 161 are held open the water is free to flow back into the cylinder or into the reservoir. This releases the pressure on 25 the diaphragm so that the parts are again in the positions shown in Fig. 2. Before the lasted shoe with its sole laid can be removed from the machine, the bell crank 179 is manipulated to open the jack valve 179 30; and since all the valves are then open and all the conduits free, the water in the whole system finds its level.

In prior applications Serial Nos. 184,347 and 287,516 filed in my name various features which are shown in the present application, among them the swinging and downwardly moving jack, the fluid control of the jack and pad, and the plate which serves both as a locating means for the sole and 45 a means for restricting the flexibility of the diaphragm to a narrow locality are shown, described and broadly claimed. Consequently nothing in the way of limitation which appears in the appended claims 50 should be construed as a dedication to the public.

In the description of the mode of operation of the machine it has been stated that first the sole is placed upon the diaphragm 55 and then the shoe is placed upon the sole. It should be understood, however, that if desired the sole may first be placed upon the bottom of the shoe and then the shoe with the sole in position upon it placed 60 upon the diaphragm.

Although the invention has been set forth as embodied in a particular machine it should be understood that the invention is not limited in the scope of its application to the particular machine which has been 70 shown and described.

Having thus described my invention, what I claim as new and desire to secure by Letters Patent of the United States is:

1. A machine of the class described having, in combination, a shoe support, a flexible presser adapted to contact with the sole of a shoe carried by the support, a self-contained fluid system including a force feed member, and means for operating said member to cause first approach of the support and the presser and then flexing of the presser about the bottom of the shoe. 75

2. A machine of the class described, having in combination, a last support or jack, 80 a presser in the form of a flexible diaphragm, a self-contained liquid system including a force feed member, and means for actuating the force feed member to cause liquid under pressure to actuate both the 85 jack and the presser.

3. A machine of the class described having, in combination, a shoe support, a flexible presser adapted to contact with the sole of a shoe carried by the support, a self-contained fluid system including a force feed member, and operator-controlled, power-operated means for operating said member to cause first approach of the support and 90 the presser and then flexing of the presser 95 about the bottom of the shoe. 100

4. A machine of the class described, having in combination, a presser for acting upon the sole of a lasted shoe, a jack for holding the shoe against the sole, a self-contained liquid system including a pump, and means for actuating the pump to cause liquid pressure to operate both the jack and the pad. 105

5. A machine of the class described, having in combination, a presser for acting upon the sole of a lasted shoe, a jack for holding the shoe against the sole, a self-contained liquid system including a force pump, and operator controlled means for actuating the pump to cause liquid pressure to operate both the jack and the pad. 110 115

6. A machine of the class described, having in combination, a presser in the form of a flexible diaphragm for acting upon the sole of a lasted shoe, a jack for holding the shoe against the sole, a self-contained liquid system including a force pump, and means for actuating the pump to cause liquid pressure to operate both the jack and the pad. 120 125

7. A machine of the class described, having in combination, a jack, a presser, a self-contained system of receptacles and conduits for liquid, a driving member, means for imparting a predetermined cycle of 130

- movement to said member, and means operated by said movement for forcing liquid under pressure to said jack and presser.
8. A machine of the class described, having in combination, a jack, a presser in the form of a flexible diaphragm, a self-contained system of receptacles and conduits for liquid, a driving member, means for imparting a predetermined cycle of movement 10 to said member, and means operated by said movement for forcing liquid under pressure to said jack and presser.
9. A machine of the class described, having in combination, a jack for supporting a 15 shoe against pressure during the sole laying operation, a sole laying member in the form of a flexible diaphragm, a container for liquid, conduits leading from the container to the jack and the sole laying member, and a pump for forcing liquid from the container through the conduits.
10. A machine of the class described, having in combination, a jack for supporting a shoe against pressure during the sole laying operation, a sole laying member in the 25 form of a flexible diaphragm, a container for liquid, conduits leading from the container to the jack and the sole laying member, and an operator controlled pump for forcing liquid from the container through the conduits.
11. A machine of the class described, having in combination, a jack for supporting a shoe against pressure during the sole laying operation, a sole laying member in the 30 form of a flexible diaphragm, a container for liquid, conduits leading from the container to the jack and the sole laying members, valves in the conduits, means for forcing liquid through the conduits and means 35 acting upon the valves for controlling the sequence in which they are operated.
12. A machine of the class described, having in combination, a jack for supporting a 40 shoe against pressure during the sole laying operation, a sole laying member in the form of a flexible diaphragm, a container for liquid, conduits leading from the container to the jack and the sole laying member, valves in the conduits, means for forcing liquid through the conduits and thereby 45 operating the valves, and springs of different strengths acting upon the valves for controlling the sequence in which they are 50 operated.
13. A machine of the class described, having in combination, a jack for supporting a shoe against pressure during the sole laying operation, a sole laying member in the 55 form of a flexible diaphragm, a container for liquid, conduits leading from the container to the jack and the sole laying member, valves in the conduits, means for forcing liquid through the conduits, and springs 60 of different strengths acting upon the valves.
- for controlling the sequence in which they are opened.
14. A machine of the class described, having in combination, a jack for supporting a shoe against pressure during the sole laying operation, a sole laying member in the 70 form of a flexible diaphragm, a container for liquid in the form of a cylinder, conduits leading from the cylinder to the jack and the diaphragm, a piston in the cylinder, and means for reciprocating the piston. 75
15. A machine of the class described, having in combination, a jack for supporting a shoe against pressure during the sole laying operation, a sole laying member in the 80 form of a flexible diaphragm, a container for liquid in the form of a cylinder, conduits leading from the cylinder to the jack and the diaphragm, a piston in the cylinder, and means for imparting to the piston movement first in a direction to force liquid from the cylinder and then in a direction 85 to draw it into the cylinder. 85
16. A machine of the class described, having in combination, a jack, a presser, a self-contained liquid system including a reservoir for the liquid, a cylinder, a conduit leading from the cylinder to the jack, a conduit leading from the cylinder to the presser, a conduit leading from the last-named conduit to the reservoir, valves in the conduits, a piston in the cylinder, and means 90 for operating the piston. 90
17. A machine of the class described, having in combination, a jack, a presser, a self-contained liquid system including a reservoir for the liquid, a cylinder, a conduit leading from the cylinder to the jack, a conduit leading from the cylinder to the 95 presser, a conduit leading from the last-named conduit to the reservoir, valves in the conduits, means acting upon the valves to determine the sequence in which they are 100 operated, a piston in the cylinder, and means for operating the piston. 100
18. A machine of the class described, having in combination, a jack, a presser, a self-contained liquid system including a reservoir for the liquid, a cylinder, a conduit 115 leading from the cylinder to the jack, a conduit leading from the cylinder to the presser, a conduit leading from the last-named conduit to the reservoir, valves in the conduits, springs tending at all times to 120 close the valves, the spring of the valve in the conduit leading to the presser being of less strength than that of the valve in the conduit leading to the reservoir and of greater strength than that of the valve leading to the jack. 125
19. A machine of the class described, having in combination, a jack or support for a lasted shoe, a flexible presser, means for holding a body of liquid at all times against 130

- the presser and positively operated means for increasing and decreasing the volume of the liquid to move the presser toward and from the jack.
- 5 20. A machine of the class described, having in combination, a last support, a box having a flexible section or pad opposite said support, and positively operated means for forcing fluid into and withdrawing it 10 from the box. 70
- 15 21. A machine of the class described, having in combination, a last support, a box having a flexible section or pad opposite said support, positively operated means for forcing fluid into and withdrawing it from the box, and means for automatically determining the length of the charging and discharging operation. 75
- 20 22. A machine of the class described, having in combination, a last support, a box having a flexible section or pad opposite said support, positively operated means for forcing fluid into and withdrawing it from the box, and means for limiting the pressure in said box to a predetermined degree. 80
- 25 23. A machine of the class described, having in combination, a last support, a box having a flexible section or pad, opposite said support, positively operated means for forcing fluid into and withdrawing it from the box, and adjustable means for determining the degree of maximum pressure exerted attained by the liquid in the box. 85
- 30 24. A machine of the class described, having in combination, a last support, a box having a flexible section or pad opposite said support, a cylinder, an oscillatory piston thereon, and a mobile incompressible power transmitter for communicating oscillations of the piston to said pad. 90
- 35 25. A machine of the class described, having in combination, a last support, a flexible pad opposite said support and having a liquid backing, a reservoir for a reserve 100
- 40 supply of liquid above the level of said pad, conduit connections for the movement of liquid back and forth between said reservoir and pad, and means for effecting movement of liquid first in one direction and then in the other direction through said conduit connections. 105
- 45 26. A machine of the class described, having in combination, a last support or jack, a flexible pad, hydraulic pressure means for flexing the pad in opposition to a last supported by the jack, means for increasing and diminishing the pressure for flexing the pad, valve mechanism for controlling said pressure, and a reservoir for liquid, 110
- 50 said valve mechanism being constructed and arranged to divert liquid from the pad to the reservoir. 115
- 55 27. A machine of the class described, having in combination, a jack, a co-operating presser in the form of a flexible diaphragm, 120
- 60
- 65
- a receptacle for holding a body of liquid against the presser, a cylinder for holding liquid, a conduit between the cylinder and the receptacle, a valve in the conduit, a reservoir for surplus liquid, a passageway from the conduit to the reservoir, a second valve in the passageway, means for operating the valves constructed and arranged to control the sequence of their opening, and means for forcing liquid past the valves. 125
28. A machine of the class described, having in combination, a jack, a co-operating presser in the form of a flexible diaphragm, a receptacle for holding a body of liquid against the presser, a cylinder for holding liquid, a conduit between the cylinder and the receptacle, a valve in the conduit, a reservoir for surplus liquid, a passageway from the conduit to the reservoir, a second valve in the passageway, means for operating the valves constructed and arranged to cause the valve in the passageway leading to the reservoir to be held closed after the other valve has been opened, and means for forcing liquid past the valves. 130
29. A machine of the class described, having in combination, a jack, a co-operating presser in the form of a flexible diaphragm, a receptacle for holding a body of liquid against the presser, a cylinder for holding liquid, a conduit between the cylinder and the receptacle, a valve in the conduit, a reservoir for surplus liquid, located at a level to maintain liquid at all times in contact with the diaphragm, a passageway from the conduit to the reservoir, a second valve in the passageway, means for operating the valves constructed and arranged to control the sequence of their opening, and means for forcing liquid past the valves. 135
30. A machine of the class described, having in combination, a jack, a co-operating presser in the form of a flexible diaphragm, a receptacle for holding a body of liquid against the presser, a reservoir for reserve liquid located above the level of the receptacle, a cylinder, conduits leading from the cylinder to the receptacle and to the reservoir, valves in the conduits, a piston in the cylinder, means for reciprocating the piston, and means for opening the valves in timed relation to the movements of each other and to that of the piston. 140
31. A machine of the class described, having in combination, a last support or jack and a presser, a sole locating plate slidably mounted adjacent to the presser, and means interposed between said plate and presser to prevent wear of the latter by the former. 145
32. A machine of the class described, having in combination, a last support or jack and a pad, mechanism for relatively operating the jack and pad, a plate slidably mounted adjacent to the pad, said plate having differently-shaped sole-locating open-

ings, and a thin plate interposed between the pad and plate, said thin plate having an opening located to register with one of the openings in the slidable plate when the latter is in position to locate a sole in position for operation.

33. A machine of the class described, having in combination, pressure applying means including a box having a flexible section or pad, means for keeping the box completely filled with a liquid to the exclusion of air and positively operated means for increasing and reducing the quantity of liquid in the box.

34. A machine of the class described, having in combination, pressure applying means including a box having a flexible section or pad, means for keeping the box completely filled with a liquid to the exclusion of air, positively operated means for increasing and reducing the quantity of liquid in the box, and means for automatically determining the maximum pressure of liquid in the box.

35. A machine of the class described, having in combination, pressure applying means including a box having a flexible section or pad, means for keeping the box completely filled with a liquid to the exclusion of air, positively operated means for increasing and reducing the quantity of liquid in the box, and means for automatically determining the duration of said increase and reduction.

36. In a sole laying machine having a last support or jack and a presser, gages for the toe and one side edge of a sole, and a heel gage constructed and arranged to be adjusted in a direction inclined relatively to the median line of a sole.

37. In a sole laying machine having a last support or jack and a presser, a sole-locating plate mounted between the jack and presser, and a heel gage adjustably carried by said plate.

38. In a sole laying machine having a last support or jack and a presser, a sole-locating plate mounted between the jack and presser, and a heel gage carried by said plate and adjustably relatively thereto in a direction inclined relatively to the median line of a sole located by said plate.

39. In a sole laying machine having a last support or jack and a presser, a plate mounted between the jack and presser, said plate having a sole-gaging opening, and a heel gage adjustably carried by said plate.

40. In a sole laying machine having a last support or jack and a presser, a plate mounted between the jack and presser, said plate having a sole-gaging opening, and a heel gage carried by said plate and adjustably relatively to the heel end of said opening in a direction inclined to the longitudinal median line of the opening.

41. In a sole laying machine having a last support or jack and a presser, a sole-

locating plate mounted between the jack and presser, and a wiper carried by said plate in position to act upon the margin of a sole at the heel end thereof.

42. In a sole laying machine having a last support or jack and a presser, a sole-locating plate mounted between the jack and presser, and a wiper carried by said plate in position to act upon the margin of a sole at the heel end thereof, said wiper being adjustable relatively to the heel end of a sole located by said plate.

43. In a sole laying machine having a last support or jack and a presser, a sole-locating plate mounted between the jack and presser, and a combined heel gage and wiper carried by said plate.

44. In a sole laying machine having a last support or jack and a presser, a sole-locating plate mounted between the jack and presser, and a combined heel gage and wiper carried by said plate, said heel gage and wiper being adjustable obliquely to the median line of a sole located by said plate.

45. A machine of the class described, having in combination, a last support or jack, a pressure-box including a flexible diaphragm, valve-controlled conduits leading respectively to the jack and to the box, means for forcing fluid through the conduits to cause the diaphragm to be pressed against the bottom of a shoe supported by the jack and to cause the diaphragm to be flexed about the bottom of the shoe, automatic means for opening the valve which controls the conduit leading to the pressure-box so as to release the pressure of the fluid on the diaphragm, and operator-controlled means for opening the valve which controls the conduit leading to the jack so as to release the pressure of the fluid on the jack.

46. A machine of the class described, having in combination, a last support or jack, a presser, a self-contained fluid system including a force feed member, and means for actuating the force feed member to cause fluid under pressure to actuate both the jack and the presser.

47. A machine of the class described, having in combination, a last support or jack, a presser in the form of a flexible diaphragm, a self-controlled fluid system including a force feed member, and means for actuating the force feed member to cause fluid under pressure to actuate both the jack and the presser.

48. A machine of the class described, having in combination, a presser for acting upon the sole of a lasted shoe, a jack for holding the shoe against the sole, a self-contained fluid system including a pump, and means for actuating the pump to cause fluid pressure to operate both the jack and the pad.

49. A machine of the class described, hav-

ing in combination, a jack, a presser, a self-contained system of receptacles and conduits for fluid, a driving member, means for imparting a predetermined cycle of movement to said member, and means operated by said movement for forcing fluid under pressure to said jack and presser.

5 50. A machine of the class described, having in combination, a jack for supporting a
10 shoe against pressure during the sole lay-

ing operation, a sole laying member in the form of a flexible diaphragm, a container for fluid, conduits leading from the container to the jack and the sole laying member, and a pump for forcing fluid from the 15 container through the conduits.

In testimony whereof I have signed my name to this specification.

LOUIS A. CASGRAIN.
